UNITED STATES PATENT OFFICE.

WILLIAM N. BRIGGS, OF PITTSFIELD, MASSACHUSETTS, ASSIGNOR TO GENERAL ELECTRIC COMPANY, A CORPORATION OF NEW YORK.

METHOD OF MAKING MOLDED ARTICLES.

Application filed January 2, 1926. Serial No. 78,780.

My invention relates to molded articles, and has for its object the provision of a simple, reliable and efficient method of making a molded article.

More specifically my invention relates to the making of molded articles from layers of sheet material impregnated with a suitable binder. As heretofore produced such articles have been built up from a plurality of layers of stampings from the sheet material, these stampings being molded together and secured by the binding material by applying pressure against the sides of the sheets, i. e., the sheets are compacted together flatwise. The stamping of the sheet material in the required shapes is attended with a great deal of waste of material. This is particularly true in the formation of molded spools for electrical windings in the construction of which the flanges have heretofore been built up from a plurality of stamped rings.

In carrying out my invention I compact the article by compressing the sheet material edgewise whereby the article can be built up from rectangular or other suitably shaped strips of material which can be cut without waste. In the making of flange rings for spools, for example, a strip of the sheet material is wound into a coil which is then formed into a ring by compacting the convolutions of the coil edgewise. This construction, furthermore, gives a much stronger article.

For a more complete understanding of my invention reference should be had to the accompanying drawing in which Figs. 1 and 2 are views showing steps in the construction of a flange ring; Fig. 3 shows the application of a ring to the cylindrical portion of the spool prior to the molding operation; Fig. 4 shows a completed spool; while Figs. 5, 6 and 7 show a modification of my invention.

Referring to the drawing, I have shown my invention in one form as applied to the making of spools from sheet fibrous material impregnated with a suitable binder. This material may and preferably is wood pulp impregnated with a phenolic condensation product. Obviously, however, any other suitable fibrous material impregnated with a binder may be used. The making of the spool can be, roughly, divided into two steps, the formation of a cylindrical por-

tion and the formation of rings which constitute flanges. These rings are placed on the cylindrical portion, and the assembled parts are then placed in a suitable mold where by the application of pressure, and heat if necessary, the spool is shaped and compacted to the desired size.

The rings forming the flanges are made from long rectangular strips of the sheet material. The strips are cut of suitable width and length to provide enough material to form a flange ring of the required size. This strip 10 is first wound in spiral formation into a loose coil as shown in Fig. 1, the convolutions or layers of the coil being preferably spaced apart somewhat as indicated in the drawing. It will be observed that the successive convolutions of the coil are wound flatwise with respect to each other so that the transverse dimension of the strip at all points is parallel with the axis of the coil. The inside and outside diameters of this coil are roughly the same as the corresponding dimensions of the completed ring. The next step is to place the coil in a suitable press by means of which pressure is applied to the sides of the coil, i. e., in a direction parallel with its axis whereby the convolutions of the strip are upset or compressed edgewise. In other words, the coil is flattened into a disk-like ring 11, as shown in Fig. 2. The pressing device is preferably a mold which defines both the inside and outside diameters of the ring.

This compressing and molding operation may and preferably is carried out while the material is cold. The phenolic binding material is not softened therefore so as to exert its maximum binding properties, but nevertheless the convolutions are compressed together and interlocked so as to adhere to a considerable extent. The cold pressed ring, as shown in Fig. 2, has a considerable amount of mechanical strength. This mechanical strength is such that the ring can be handled in the same manner and has to all intents and purposes the same mechanical strength as a ring built up from a plurality of stampings from the sheet material.

The cylindrical portion of the spool is formed in a similar manner from a strip or sheet of the fibrous material which is rolled into a cylinder 12, as indicated in Fig. 3.

When one or more intermediate flanges are to be formed on the spool, a ring 13 constructed as described in connection with Figs. 1 and 2 is placed on the cylinder in the proper position and the assembled parts then placed in a mold. By means of the mold enormous pressures are applied and likewise sufficient heat to soften the phenolic impregnating material. The mold also upsets each end of the cylinder to form flanges 14 and 15 (Fig. 4) on the ends in substantially the manner described in connection with Figs. 1 and 2. With these end flanges, however, heat is applied at the same time that the sheet material is compressed edge-wise so that the flanges at the end are formed in one operation instead of being first compressed cold and then subsequently further compressed while hot as is the case with the central flange. If desired, however, the end flanges may be formed from cold pressed rings slipped in the cylindrical portion, which in such case would have substantially the length of the completed spool.

This molding operation, as previously indicated, compresses the material into the desired shape and size, the binding material being then softened by the application of heat. The binding material is thus caused to not only bind the fibers of the respective sheets together, but also the sheets themselves. The central flange ring 13 is thereby secured to the cylindrical portion and shaped to form the central flange 16 of the completed coil. After the spool has been removed from the mold and the binding material allowed to harden the result is a solid homogenous spool having both great mechanical strength and dielectric strength.

As previously indicated, this principle in the formation of molded articles of compressing laterally loosely assembled layers or sheets of treated fibrous material has general application in the formation of molded articles, in addition to its application to the making of spools. In Figs. 5, 6 and 7, I have shown its application to the making of molded bars. A plurality of strips 17 (Fig. 5) of a suitable size to make the finished article are placed in a mold and compressed edge-wise while cold into a square bar 18, as shown in Fig. 6. As indicated in Fig. 5 the strips 17 do not fit tightly side by side in the mold, sufficient space being left to permit the strips to be upset. The bar 18 has mechanical strength to a marked degree, the strips being interlocked together by the upsetting operation. The next step is to place the cold pressed bar 18 into a heated mold where pressure is again applied concurrently with sufficient heat to soften the binding material, preferably phenolic condensation product. The final step compresses the bar to the desired dimensions, after which the bar is taken out and allowed

to cool. The completed bar 19 is shown in Fig. 7.

I have found that bars and other articles produced in this manner have much greater mechanical and dielectric strength than articles formed by pressing the sheet material together flatwise. The strips when pressed together flatwise tend to separate upon the application of a considerable force. When the strips are upset, however, in accordance with my invention, they are interlocked so that a solid homogenous structure is formed.

It will be observed that the lengths of sheet material are placed loosely together to form a body whose dimensions in a plane at right angles to the sheet material are approximately equal to a cross sectional dimension of the completed article. The dimension of the body formed by the loosely assembled lengths in the plane of the sheet material, however, is many times the corresponding dimension of the completed article. For example, the coil of Fig. 1 has over-all dimensions in a plane at right angles to the sheet which are substantially the same as the corresponding dimensions of the flange ring 11 of Fig. 2. The dimension of the coil at right angles to this plane, however, i. e., the height, is many times the height of the flange ring. Similarly, in Fig. 5, the loosely assembled strips 17 form a body which has dimensions in a plane at right angles to the strips substantially equal to the similar dimension of the completed article. During this first cold pressing operation the only dimension changed to any extent is the one at right angles to this plane. The articles 11 and 18 of Figs. 2 and 6 resulting from the cold pressing operation have substantially the dimensions of the completed article and the finishing molding operation compresses these articles somewhat uniformly.

While I have described my invention as embodied in concrete form and as operating in a specific manner in accordance with the provisions of the patent statutes, it should be understood that I do not limit my invention thereto, since various modifications thereof will suggest themselves to those skilled in the art without departing from the spirit of my invention, the scope of which is set forth in the annexed claims.

What I claim as new and desire to secure by Letters Patent of the United States, is:—

1. The method of forming a molded article which consists in loosely assembling a plurality of layers of sheet material, compressing said layers edge-wise while cold into a solid mass having approximately the dimensions desired, and then further compressing said mass uniformly in all directions in a heated mold.

2. The method of forming a molded

article which consists in providing strips of fibrous material impregnated with a phenolic condensation product, placing said strips in a mold and compressing them edgewise while cold into a solid integral body, removing said body from said cold mold, placing said body in a heated mold, and further compressing said body while heated to a temperature sufficient to soften said impregnating material.

3. The method of forming the flange ring a spool which consists in providing a strip of fibrous material impregnated with a phenolic condensation product, winding said strip into a spiral coil, and then compressing said coil edgewise while cold so that the turns are crushed into interlocking relation and secured by said impregnating material to form a solid integral body.

4. The method of forming a spool which consists in winding a strip of treated fibrous material into a loose coil, applying pressure to flatten said coil into a ring, placing the ring thus formed on a cylindrical portion, and then compacting and forming the cylinder and ring in a heated mold.

5. The method of forming a molded spool which consists in winding a strip of treated fibrous material into a loose coil, applying pressure to flatten said coil into a ring while cold, winding a cylinder from a sheet of said fibrous material, placing the previously formed ring on said cylindrical portion in position to form a central flange, and then compacting and forming the cylinder and ring in a heated mold so as to upset the ends of said cylinder to form end flanges.

6. The method of forming a molded spool from fibrous sheet material impregnated with a phenolic condensation product which consists in forming a flange for the spool separately by winding a strip of said material into a loose coil and flattening said coil while cold in the direction of its axis into a solid ring, rolling a sheet of said material into a cylinder, placing said ring on said cylinder, and then compacting and shaping the cylinder and ring into a solid integral body in a heated mold.

In witness whereof, I have hereunto set my hand this 28 day of December, 1925.

WILLIAM N. BRIGGS.
